United States Patent Office

Des. 191,607
Patented Oct. 24, 1961

191,607

TRUCK

Ralph G. Rutman, Allentown, Pa., assignor to Mack Trucks, Inc., Plainfield, N.J., a corporation of New York

Filed June 9, 1961, Ser. No. 65,538

Term of patent 14 years

(Cl. D14—3)

Des. 191,607

PAGE 2

FIG.2.

Des. 191,607

FIG. 3.

FIG.4.

The dominant feature of my design resides in the portions shown in full lines.

I claim:

The ornamental design for a truck, as shown and described.
